Albert E. Powers of Lansingburgh, N.Y.

DES. 1985

Letters Patent No. 13,785-Dated Aug 16, 1864.

Design for Floor-Cel. Cloths.

The schedule referred to in these Letters Patent and making part of the same.

To all whom it may concern.

Be it known that I, Albert E. Powers, of Lansingburgh, in the County of Rensselaer and State of New York, have invented or produced new and original design for Floor-Cel. Cloths or other fabrics; and I do hereby declare that the following is a full and exact description of the same. The pattern is drawn to represent a lattice work of Gothic style, with ornaments cross upon the openings of the lattice, the pattern and all its details being shown upon the accompanying drawings, which are hereby declared to be part of this specification.

And what is claimed as my invention and desired to be secured by Letters Patent, is - The design or pattern shown upon the accompanying drawings.
